TELEPHONE REGISTER CONTROL SYSTEM

Gerald Deakin, New York, N. Y., assignor to International Standard Electric Corporation, New York, N. Y., a corporation of Delaware

Application April 21, 1944, Serial No. 532,141

13 Claims. (Cl. 179—18)

1

This invention relates to new and useful improvements in register controlled telephone systems.

The object of the invention is to provide an arrangement in which an idle register controller is automatically connected with a link to which a line finder or other non-numerical switch has been started to connect a calling line.

According to a feature of this invention, the first selector is operated simultaneously with the first digit switch of the register. If certain first digit or digits are dialled, e. g. if a local connection is desired, then the register is promptly detached, and the calling subscriber continues to control the establishment of the connection by directly operating the other selectors over the first selector set by the register. If, however, the first digit indicates a different type of connection, e. g. an inter-office connection, then the first selector is released, and the register remains attached and controls the completion of the connection in accordance with the other impulses received from the calling subscriber.

In the drawings which diagrammatically represent as much of an automatic telephone system as is necessary for an understanding of the invention:

Fig. 1 is a block diagram showing the relationship of the other figures to one another and to the rest of an exchange;

Fig. 2, the circuits of a well-known line finder;

Fig. 3, the circuits of the link between the line finder, first group selector and the register;

Figs. 4, 4a and 4b, the register; and

Fig. 5, the circuits of a well-known type of group selector.

GENERAL

In the present system, a register controller such as the one described in detail in my co-pending application, Serial No. 521,160, filed February 5, 1944, may, after simplification, be easily added to new or existing step-by-step systems where office prefix translation or register control is necessary or desirable. In step-by-step offices equipped with 200-point finders like the one shown in Fig. 2, no change whatsoever need be made in the existing equipment other than to connect in the new equipment indicated between the vertical dotted lines in Fig. 1 and to remove the dialing tone from the first group selector (Fig. 5). A simple, two-relay selector link, referred to herein as an S-link (Fig. 3) is wired in between the 200-point finder and the first group selector. These S-links are connected in simple selector-register

2

links, referred to herein as SR-links (Fig. 3), the purpose of which is to concentrate traffic upon groups of 60 registers, thereby reducing the total number of registers to a minimum. The register circuit is shown in Figs. 4, 4a and 4b. The translator links are like the one shown in said application, Serial No. 521,160, filed February 5, 1944.

The registers and translating equipment may be added, so to speak, one first group level at a time, that is, while a register is picked up by every new call. It is immediately dropped after the dialing of the first digit should it be unnecessary to translate the office prefix which was dialed to designate the first group level. To make this possible, the register operates the first group selector in parallel with the first digit switch. If translation is unnecessary, then the register drops off and dialing continues over the selected first group level in the ordinary way. However, should translation be found necessary, then the first group selector is restored to normal and the register takes full charge of the routing of the call.

OPERATION OF CIRCUITS

When a subscriber originates a call, a 200-point step-by-step finder (Fig. 2) is allotted and that finder grounds at a front contact of the A relay the "p" wire, thus placing a ground over back contacts of SBR and SAR, and resistor R1 (Fig. 3) on the T terminals of the S-link in the banks of the S-link finders of the SR-links. The common starting relay CSR (Fig. 3) is energized from the same ground on the "p" wire through resistors R1 and R2 substantially simultaneously with the starting of the line finder. The wires leading to the first group selector are not disconnected at this stage because the 200-point finder may reach the near terminals in its bank before an SR-link or the register is connected. Current is supplied to the line during this interval from the A relay in the first group selector (Fig. 5) but, as previously stated, the dialing tone is removed from the first group selector and is not heard until a register is connected.

SR-link operates

When CSR (Fig. 3) operates, it energizes the P1 power magnets of all idle S-link finders. The first link finder to select the calling S-link seizes it and makes it busy. Test relays T1R and T2R operate in the usual way and check for a double connection. T2R energizes P2 and causes the register finder to search for an idle register and when one is found, T3R and T4R seize the

register, make it busy, and check for a double connection, all in the usual way. T4R operates RAR which closes the circuit of brushes A to G through to the register.

Register operates subscriber dials

When the calling line circuit is closed over the A and B brushes by RAR (Fig. 3), the stepping relay DR (Fig. 4) operates and energizes slow releasing relay R1R which, in turn, energizes XR (Fig. 4b) and slow releasing relay RCR (Fig. 4). The closure of the E brush circuit by RAR (Fig. 3) closes the dialing tone circuit, which is heard by the calling subscriber.

R1R (Fig. 4) grounds the "c" wire and energizes SAR (Fig. 3) and RBR. SAR disconnects the first group selector from the calling line and in place thereof connects it over brushes F and G to a closed loop in the register, including the back contacts of DR1, RVR and RKR (Fig. 4). RBR (Fig. 3) opens the circuit of the common starting lead and retains RAR energized. Relays T1R and T2R release when SAR is energized. Relays T3R and T4R are released when RCR (Fig. 4) breaks its back contact.

When the subscriber dials, DR (Fig. 4) makes its back contact in the usual way and advances the digit switch D1 (Fig. 4a) over terminal 1 brush A of PI. DR1 (Fig. 4) operates in parallel with D1 and each time it opens its back contact, it opens the loop above referred to, and the first group selector steps up one level. If, for instance, the digit 3 is dialed, then digit switch D1 is advanced to position 3 and the first group selector to level 3. At the end of the first series of pulses, PI (Fig. 4a), which has been energized over the front contact of R2R, is released and its brushes go to position 2. In case the register is retained, digit switches D2 to D6 or D7, depending upon whether six or seven digits are dialed, are advanced in the same manner as was digit switch D1.

Office prefix translation not required

For the purpose of this description, it is assumed that office prefix translation will not be required when first group levels, 1, 8, 9 and 0 are dialed. When any of these four levels is dialed, a circuit is established, when PI (Fig. 4a) goes to position 2 following the dialing of the first digit, from ground, brush C and terminal 2 of PI, brush A and terminal 1 of PO, brush A of D1, terminal 1, 8, 9, or 0, as the case may be, to brush D of the SR-link (Fig. 3). The grounding of brush D energizes SBR which opens the circuit of SAR and locks up to the "p" wire now grounded by the first group selector. SAR releases and connects the calling line straight through the first to the second group selector or other trunk picked up by the first group selector. RBR, which is in series with SAR, releases and de-energizes RAR. RAR opens the brush circuits to the register and DR (Fig. 4) falls away. DR releases R1R which releases XR (Fig. 4b) and slow releasing RCR (Fig. 4). XR restores the digit switches to normal and when RCR makes its back contact, it restores PI to normal. When PI reaches position 1, the test circuit of the register is again closed and the register is ready for the next call. The reason for making RCR slow is to allow ample time for all switches other than PI to return home before the register is again placed in operation.

Office prefix translated

When the first group digit dialed is 2 to 7, the following circuit is closed when PI goes to posi-

tion 2: from ground, brush C, terminal 2 of PI, brush A terminal 1 of PO, brush A of D1, terminals 2 to 7, one winding RVR, brush D of PI, terminals 2 to 7, winding RTR1, back RTR2 to battery. RVR (Fig. 4) operates, locks up and opens the loop holding the first group selector, which releases and returns to normal. RTR1 (Fig. 4a) calls in a two-digit translator link as described in detail in application, Serial No. 521,160, filed February 5, 1944, and the two or three-digit office prefix, as the case may be, is translated by the translator link into two, three or four successive selecting operations, as required.

Pulsing

We will assume that a six-digit number is being dialed, which comprises a two-digit office prefix. When translation is complete, RTR3 (Fig. 4a) operates and a circuit is established from ground, front RTR3, terminal 1, brush B of PO, back and winding RVR (Fig. 4) to battery. RYR operates and locks up over a front contact of RCR. RYR places high tension battery on the triode circuit and closes the trunk loop, circuit from ground, one winding of the A relay of the first group selector (Fig. 5), brush G of the SR-link (Fig. 3), back RKR, in multiple with brush B, terminal 1 of PT (Fig. 4a), rectifier S(+) (Fig. 4), winding of relay PR(+), front RYR, front RVR, back DR1, F brush, other winding of A relay of the first group selector to battery. The A relay of the first group selector and PR(+) of the register operate in series. PR(+) closes the circuit of RKR from ground on the B brush of PO, front RYR, back GVR, back GSR, front PR(+), winding RKR, 10-cycle interrupter to battery. When the live segment of the interrupter closes the circuit of RKR, the latter operates and energizes the magnet PT of the marker switch and of relay RJR. RJR locks up over the back contact of GVR and GSR and short-circuits PR(+) and the rectifiers. PR(+) releases but not before its front contact is short-circuited by RJR.

When the interrupter opens the circuit of RKR, PT is released and its brushes A and B go to position 2, in which brush B removes the short circuit from the pulsing contact of RKR. The purpose of thus short-circuiting the first pulse is to ensure the full length of the first pulse sent out over the trunk loop.

When the interrupter closes the circuit of RKR for the second time, PT is again energized and the trunk loop is opened at the back contact of RKR, thus causing the first group selector to step up one level.

These operations continue until the required number of pulses have been sent out. Assume, for example, that three pulses are to be sent out. PT will go to position 5 when RKR releases after the third pulse. Brush A of PT in position 5 places potential PN3 on the grid of V2, which potential is also placed on the grid of V1 by the translator. Gas valve GV fires in the usual way and operates GVR. GVR opens the circuits of RKR and RJR, the latter releases and the former is not again energized when the interrupter next closes the battery circuit. RKR restores over a back contact PT to its home position.

GVR operates slow releasing relay GSR. GSR energizes PO and opens the high tension battery circuit which de-ionizes GV and releases GVR. GVR releases GSR and when GSR breaks its front contact, PO goes to position 2.

The first group selector may pick up the second group selector or other trunk before or after PO

goes to position 2. The second selector is held energized by the fundamental circuit loop which again includes PR(+) since RJR is not now energized. As long as the circuit of the B brush of PO is held open at the back contact of GSR, RKR cannot be operated and pulses therefore are not sent out. However, when GSR breaks its front contact and makes its back contact, the circuit of relay RKR is again closed, this time over terminal 2, brush B of PO, and brush A, segment 1/11 of D2. GSR is made sufficiently slow releasing so as to allow ample time for the change-over in the step-by-step selector which normally takes place during the long closure of the line between the dialing of the digits.

The second, third or fourth series of pulses of the office prefix, as the case may be, are sent out in the same manner as the first series. When relays RTR4 and RTR5 (Fig. 4a) are energized, the office prefix consists of four selections. When only RTR5 is energized, the office prefix consists of three selections and when neither of the relays is energized, the office prefix consists of only two selections.

After the office prefix selections have been made, PO goes to position 5 and the B brush of PO from now on is grounded direct by brushes A of the digit switch D3 to D6. The four selections of the office number are made by the pulsing circuit in the same manner as the office prefix selection. Upon completion of all selections, PO goes to position 9 and the D brush of the SR-link is grounded by the A brush of PO. SBR (Fig. 3) of the S-link is energized which releases SAR and RBR of the SR-link. SAR connects the calling line through to the completed connection for ringing or busy tone, as the case may be. The SR-link is released when RBR breaks its front contact and releases RAR. The opening of the line circuit releases DR (Fig. 4) which releases RIR which, in turn, releases XR and RCR, after which all switches and relays in the register return to normal.

In case a seven-digit number is dialed, RTR2 (Fig. 4b) is energized and, in turn, energizes RTR6 (Fig. 4a), which locks up, RTR6 transfers the release circuit over brush A of PO, from terminal 9 to terminal 10, whereby on a seven-digit call, the D brush of the SR-link is not grounded until after the seven dialed digits have been disposed of.

Out-trunking to universal office

Out-trunking to a universal office, i. e. one in which the switches are controlled over a multi-potential fundamental circuit, is done in the same manner as out-trunking to a step-by-step office with this exception, that the trunk wires to a universal office are reversed until a T-register thereat is connected. The initial trunk loop is closed through rectifier S(—) (Fig. 4) and resistor R. PR(+) is not energized until the distant T-register is connected, at which time current is reversed. From there on the register (Figs. 4-4b) operates as on a call to a step-by-step office.

In-dialing to automatic P. B. X's

The register, Serial No. 521,160, filed February 5, 1944, is arranged for in-dialing to an automatic P. B. X. The present register is not so arranged but such in-dialing may be done by waiting for the P. B. X dialing tone which follows after the A-register (Figs. 4-4b) is released. In order to have only one set of instructions in the directory for dialing into P. B. X's in a mixed network, the

register of the last-mentioned application may be easily changed to reconnect the dialing tone a second time just after dialing the P. B. X conversion number. This dialing tone would always be received immediately after dialing the P. B. X number; there would be no delay.

False calls

Relay TAR1 (Fig. 4) is included in the initial 10 control loop of the first group selector. Should the subscriber fail to dial within 20-40 seconds, relays TAR2 and TAR3 will operate. TAR3 grounds terminals 1 and 2 of bank B of PO. Digit switches D1 and D2 in their home positions apply 15 potentials PN9 and PN1, respectively, to terminals 1 and 2 of the C bank of PO. Thus, when TAR3 operates, the call is automatically extended to No. 91, after which the D brush of the SR-link is grounded by brush D of PO when PO goes to position 3. The register and SR-link release. The number "91" has been arbitrarily chosen; any other two-digit number may be cross-connected to the B banks of D1 and D2.

What I claim is:

- 25 1. In a telephone system, a plurality of lines, means including normally inactive non-numerical and numerical switches for connecting a calling with a called line, a link between said switches, a plurality of registers adapted to be set by calling 30 lines for controlling the operation of the numerical switches, normally inactive switching means for connecting an idle register with a non-numerical and a numerical switch, and means operable upon the initiation of a call for substantially simultaneously starting a non-numerical switch and the switching means to establish a connection between the calling line and a numerical switch and between an idle register and the last-mentioned connection.
- 35 2. The system according to claim 1, characterized in that the non-numerical switch is a line finder.
- 40 3. The system according to claim 1, characterized in that the switching means includes a plurality of link finders adapted to hunt for the last-mentioned connection.
- 45 4. The system according to claim 1, characterized in that the switching means includes a plurality of register finders adapted to hunt for an idle register.
- 50 5. In a telephone system, a plurality of numerically designated lines, means including a plurality of selectors for connecting a calling with a called line, a plurality of registers variably operable by a calling line in accordance with the digits of the called number to control the setting of the selectors, one after the other, to establish the desired connection, means operable upon the initiation of a call for connecting an idle register with the calling line, means operable when the called number comprises certain combinations of digits for releasing the connected register after the setting of all the selectors, and means for releasing the register after the setting of the first 55 one of the selectors if the called number comprises a predetermined digit.
- 60 6. In a telephone system, a plurality of numerically designated lines, means including a plurality of selectors for connecting a calling with a called line, a plurality of registers, each having a plurality of digit switches variably operable by digits of the called number dialed over the calling line, switching means for connecting an idle register with a calling line, means in the registers to 65 connect the associated digit switches, one after

the other, with successive selectors to control their setting, means for releasing the connected register after the setting of all the selectors, means in the register for simultaneously setting the first selector with the first digit switch, means operable in response to a first digit of a certain numerical value for releasing the connected register upon the receipt of the first digit from the calling line, and means operable thereupon and controlled directly by the additional digits dialed over the calling line for controlling the setting of the other selectors over the operated first selector.

7. The system according to claim 6, characterized in that the selectors are step-by-step selectors responsive to directive impulses, and means in the register for repeating and sending to the selectors impulses corresponding to the digits dialed over the calling line.

8. The system according to claim 6, characterized by means in the register operable after the setting of the first selector in accordance with a digit of another numerical value for releasing the first and then setting other selectors to establish the connection.

9. The system according to claim 6, characterized by a translator, means for associating the translator with the register to control the setting of the selectors in accordance with digits different from but bearing a predetermined relationship to the digits dialed by the calling line, the last-mentioned means being operated only in response to the dialing of a predetermined first digit of other than said certain numerical value.

10. The system according to claim 6, characterized in that a relay associated with the first selector has contacts for connecting the calling line with the first selector and contacts for connecting the register with the first selector, and a circuit for said relay controlled by the connected register.

11. The system according to claim 6, characterized in that a relay associated with the first selector has back contacts over which the calling line, and front contacts over which the register is connected with the first selector, and means controlled over a back contact of said relay for operating the switching means to connect an idle register with the calling line and with said front contacts.

12. In a telephone exchange system, a plurality of subscribers' lines, means including groups of line finder and selector switches for connecting a calling with a called line, each of said switches having a bank of terminals and a set of wipers cooperating therewith, the subscribers' lines ter-

minating in the banks of the line finders, a link connecting the wipers of each finder with the wipers of a selector, a plurality of registers, a hunting switch for connecting an idle register with a link, means operable upon the initiation of a call for simultaneously starting a finder and the hunting switch, means controlled by the calling subscriber for operating the register in accordance with the called number, means including a fundamental circuit controlled by the register for operating the selector for establishing the connection to the called line, a relay in each link controlling the continuity of the link and the connection of the fundamental circuit therewith, and a circuit for said relay controlled by the connected register.

13. In a telephone exchange system, a plurality of subscribers' lines, means including groups of line finder and successive stages of numerical group and final selector switches for connecting a calling with a called line, each of said switches having a bank of terminals and a set of wipers cooperating therewith, the subscribers' lines terminating in the banks of the line finders and final selectors, a link connecting the wipers of each finder with a first group selector, a plurality of registers, a plurality of hunting switches for connecting an idle register with a link, means operable upon the initiation of a call for simultaneously starting a line finder and said hunting switches to connect over a line finder and a hunting switch an idle register with the calling line, means controlled by the calling subscriber over the last-mentioned connection for operating the register in accordance with the called number, means including a fundamental circuit controlled by the register for successively operating the group and final selectors for establishing the connection to the called line, a relay in each link having back contacts over which the first selector and line finder wipers are normally connected, front contacts for said relay over which the fundamental circuit is connected with the first selector, and an energizing circuit for said relay controlled by the selected register.
